United States Patent Office

Des. 220,130
Patented Mar. 9, 1971

220,130

REAR SCREEN SOUND PROJECTOR

Richard Hart, 1196 S. Main St., Lombard, Ill. 60148

Filed Jan. 2, 1970, Ser. No. 20,751

Term of patent 14 years

Int. Cl. D16—04

U.S. Cl. D61—1

FIG. 1

FIG. 2

FIG. 3

FIG. 1 is a perspective view of the inventive projector showing the front face and left side thereof;

FIG. 2 is a rear elevation of the projector of FIG. 1; and

FIG. 3 is a right side elevation of the projector of FIG. 1.

I claim:

The ornamental design for a rear screen sound projector, substantially as shown.
